UNITED STATES PATENT OFFICE.

HENRY W. CLOUGH, OF TOPEKA, KANSAS.

GRINDING-MILL.

SPECIFICATION forming part of Letters Patent No. 790,619, dated May 23, 1905.

Application filed October 22, 1904. Serial No. 229,592.

To all whom it may concern:

Be it known that I, HENRY W. CLOUGH, a citizen of the United States, residing at Topeka, in the county of Shawnee and State of 5 Kansas, have invented a new and useful Grinding-Mill, of which the following is a specification.

This invention relates to grinding-mills, more particularly to mills for grinding feed 10 of various kinds, and has for its object to produce a device of this character simple in construction, inexpensive to manufacture, efficient and rapid in action, and adapted for the reduction of any of the various forms of feed 15 ing products or materials.

With these and other objects in view, which will appear as the nature of the invention is better understood, the same consists in certain 20 novel features of construction, as hereinafter 25 fully described and claimed.

In the accompanying drawings, forming a part of this specification, and in which corresponding parts are denoted by like designating characters, is illustrated the preferred 30 form of the invention capable of carrying the same into practical operation, it being understood that the invention is not necessarily limited thereto, as various changes in the shape, proportions, and general assemblage 35 of the parts may be resorted to without departing from the principle of the invention or sacrificing any of its advantages.

In the drawings thus employed, Figure 1 is a side elevation with one side of the supporting-frame removed. Fig. 2 is a vertical section on the line 2 2 of Fig. 1. Fig. 3 is a plan view in section on the line 3 3 of Fig. 2. Fig. 4 represents a modified form of the construction. Fig. 5 represents another modified form of construction. Fig. 6 is a view similar to Fig. 2, representing another modified form of construction in section on the line 6 6 of Fig. 7. Fig. 7 is a section on the line 7 7 of Fig. 6 with the movable member 45 detached. Fig. 8 is a view of one of the stationary plates detached, illustrating a modification in the arrangement of the grinding-furrows. Figs. 9, 10, and 11 are other modified forms of the construction.

50 In the improved device is comprised gener-

ally a stationary member having one end straight and the other end curved outwardly and a member having grinding-furrows and mounted for movement parallel to the straight portion of the stationary member.

In the improved device is also comprised approved means for constructing, mounting, and operating the different members and adjusting the same, and to this end the improved device comprises side members 10 11, spaced 55 apart and connected by transverse stay-rods 12 and mounted upon base members 13 14, as by bolts 15 16. The side members 10 11 are also provided with vertical channels 17 18 and inwardly-extending integral ears 19, 20, 60 21, and 22. Mounted to swing upon the upper pair of the stay-rods 12 are members 23 24, curving outwardly at the upper ends and provided with spaced grinding-furrows 25 26, respectively, in their adjacent faces. Pivoted 65 by their inner ends to the members 23 24, near their lower straight portions, are threaded rods 27 28 29 30, passing slidably through unthreaded apertures in the ears 19 20 21 22 and provided exteriorly of the ears with nuts 70 31, 32, 33, and 34. By this means the free ends of the members 23 24 may be adjusted laterally and prevented from inward movement, while at the same time free to move outwardly, as will be obvious.

Attached to the side members 10 11 are yoke-frames 35 36, having central threaded apertures in which adjusting screw-rods 37 38 operate, the screws provided with nuts 39 40. Springs 41 42 surround the screw-rods for 85 bearing by their ends, respectively, against the members 23 24 and the nuts 39 40 to yieldably support the lower ends of the swinging members 23 24 in position, as hereinafter explained. Disposed for vertical movement between the members 23 24 is an intermediate member 43, having ribs 44 45 upon its ends for engaging the channels 17 18 in the side members 10 11 and also provided with spaced 90 grinding-furrows 46 47 in its opposite faces.

Attached transversely of the base members 13 14 is a bar 48, adjustable upon the base members, as by bolts 49 50 passing through apertures 51 52 in the same. Depending from the bar 48 is a hanger 53, in which an oper- 100

ating-lever 54 is pivoted at 55, the lever being likewise connected, as by links 56, to the intermediate member 43. The operating power will be applied to the lever, as by a rod 57, leading from any source of power, such as a windmill or the like.

The lever 54 is provided with a plurality of spaced apertures to enable the lever to be adjusted to any required extent to change the leverage, and thus adapt the device to different kinds or conditions of the feed material to be reduced. A feed-hopper 58 is supplied to receive the material and guide it into the spaces between the curved members 23 24 and the intermediate member 43. By this arrangement it will be obvious that when thus assembled and the intermediate member rapidly reciprocated the material will be gradually reduced and finally discharged at the lower side in finely-divided particles, the fineness being determined by the adjustment controlled by the nuts 31, 32, 33, and 34, as before stated.

The outwardly and upwardly curving form of the members 23 24 is an important feature of the invention, as the grinding-surfaces are thereby very materially increased and all tendency to clogging obviated, no matter how large the supply of material may be, the coarser particles being first acted upon within the larger area nearer the hopper and partially reduced and then reduced to a finer and still finer extent as they approach the final point of discharge, where the members 23 24 and the intermediate member are formed with substantially parallel surfaces. The action is thus very rapid and thorough, as the grinding effects are produced during both the upward and downward strokes of the intermediate member, especially in the lower portion, where the finer reducing takes place.

The device may be constructed for fine or coarse grinding, as may be required, as the "dress" of the grinding-surfaces may be of any degree of fineness. The novel form of the members 23 24 thus very materially increases the rapidity of the action and correspondingly increases the quantity of the product within a certain predetermined time. The rapidity and thoroughness of the reduction is thus materially increased without increase in the expense of construction or the power required to operate the mill.

The device may be constructed in any desired size, and any required power may be employed to operate it, but is more particularly adapted for operation by windmill-power.

In Fig. 4 a modified form of the device is shown wherein furrowed rollers 60 61 are inserted in the members 23 24 for coaction with the intermediate member 43, and in Fig. 5 another modified form of the device is shown, with the intermediate member 43 replaced by a furrowed disk 62, mounted for rotation upon a shaft 63 and operating through a slot in the

side member and between the members 23 24, 65 which may be employed when a continuous motion in one direction is desired—as, for instance, when power other than a windmill is employed. Any suitable means may be employed for operating the shaft 63. The roller members may be located at or near the lower ends of the curved portions of the members 23 24, as in Figs. 6, 7, and 10, or at or near the upper end of the curved members, as in Fig. 9, and the rollers may be furrowed, as 75 in Figs. 4, 6, 7, and 9, or smooth or without furrows, as in Fig. 10, according to the work required or the condition or quality of the material to be reduced. The members 23 24 may also be without the grinding-furrows, as 80 in Fig. 4, for reducing some kinds of material. The roller may also be arranged for adjustment at one end, as in Figs. 6 and 7, by means of a screw-rod 64, operating from a sleeve 65 on the shaft 66 of the roller, and 85 controlled by nuts 67 68, bearing upon brackets 69 70 on the casing, as shown in Figs. 7 and 11, so that the furrows of the roller may be caused to operate at an angle to the furrows on the member 43 or 62, as will be obvious. By this arrangement both a crushing and cutting or shearing action is obtained, which is very efficient in reducing certain kinds of material. The furrows in the members 23 24 or in the movable member 43 may 95 also be disposed at an angle to the horizontal plane, as indicated in Fig. 8, if required; but none of these modifications will be a departure from the principle of the invention, as they all produce substantially the same results. 100

Having thus described the invention, what is claimed is—

1. In an apparatus of the class described, a stationary grinding member having one end straight and the other end curved, and a second grinding member movable in a plane substantially parallel with the straight portion of the first-named member.

2. In an apparatus of the class described, a pair of stationary grinding members the lower end of each of which is straight and the upper end of each of which curves outwardly, and a second grinding member arranged between the said members and having a movement parallel with the straight portions thereof.

3. In an apparatus of the class described, a stationary grinding member having its lower end straight and its upper end curved and provided throughout its length with grinding-furrows, means for adjusting the said member, and a second member having grinding-furrows and movable in a plane parallel to the straight portion of the first-named member.

4. In an apparatus of the class described, a stationary grinding member having its lower end straight and its upper end curved, and provided on its inner face with grinding-furrows, a grinding-roller disposed transversely

of the member, and a second grinding member movable in a plane parallel with the straight portion of the first-named member.

5. In an apparatus of the class described, a stationary member having one end curved and its other end straight and provided on its inner face with grinding-furrows, a grinding-roller mounted for rotation transversely of the curved portion of the member, and a second grinding member disposed for movement parallel with the straight portion of the first-named member.

6. In an apparatus of the class described, a stationary grinding member having one end straight and the other end curved, and provided on its inner face with grinding-furrows, a grinding-roller mounted for rotation transversely of the curved portion of the member, and means for adjusting the roller to cause it 20 to operate at an angle to the furrows of the stationary member.

7. In an apparatus of the class described, a pair of grinding members the upper ends of which are reversely curved, and the lower 25 ends of which are straight, and having their opposing faces provided with grinding-furrows, said members being adapted to swing at their upper ends, means for adjusting said members, and a second grinding member having 30 parallel sides and disposed for movement between the straight portions of the first-named members.

8. In an apparatus of the class described, spaced side members connected transversely and provided with guide-channels and with inwardly-extending ears, reversely-curved 35 grinding members mounted to swing between the side members and having grinding-furrows on their contiguous faces, adjusting-rods 40 connected to the curved members and having a sliding engagement with the ears, nuts carried by the rods, a second grinding member interposed between the first-named members and having ribs to engage the guide-channels,

45 springs connected with the side members and bearing against the first-named grinding members, and means for reciprocating the intermediate grinding member.

9. In a device of the class described, spaced side members connected by transverse tie-rods and provided with guide-channels, reversely-curved members mounted to swing between said side members and having spaced grinding-furrows in their contiguous faces, an intermediate member disposed between said curved members and having parallel sides provided with spaced grinding-furrows and with 50 ribs for engaging said guide-channels, yoke-frames connected by their ends to said side frames and having central threaded apertures, threaded rods operating in said apertures and provided with adjusting-nuts between said yoke-frames and curved members, and springs between said adjusting-nuts and curved members. 55

10. In a device of the class described, spaced side members connected by transverse tie-rods and mounted upon a supporting base-frame, reversely-curved members mounted to swing between said side members and having spaced guiding-furrows in their contiguous faces, an intermediate member disposed between said curved members and having parallel sides provided with spaced grinding-furrows, a fulcrum-bar adjustably connected to said base-frame, an operating-lever adjustably pivoted to said fulcrum-bar and likewise adjustably connected at one end to said intermediate member, and means for applying power to the other end of said operating-lever. 70 75 80

In testimony that I claim the foregoing as my own I have hereto affixed my signature in the presence of two witnesses.
